UNITED STATES PATENT OFFICE.

JAMES A. HURLEY, OF BOSTON, MASSACHUSETTS, ASSIGNOR OF ONE-HALF
TO EDWIN A. WHITE, OF SAME PLACE.

BRAKE MECHANISM FOR ELEVATORS.

SPECIFICATION forming part of Letters Patent No. 326,504, dated September 15, 1885.

Application filed July 25, 1885. (No model.)

To all whom it may concern:

Be it known that I, JAMES A. HURLEY, of Boston, county of Suffolk, and State of Massachusetts, have invented an Improvement in 5 Brake Mechanism for Elevators, of which the following description, in connection with the accompanying drawings, is a specification, like letters on the drawings representing like parts.

10 This invention is an improvement upon Letters Patent of the United States No. 214,539, granted April 22, 1879, and has for its object to produce a brake mechanism for elevator-wheels which shall be positive in operation 15 and cheap and simple to construct.

This invention consists, essentially, of a power-wheel combined with a brake-shoe pivoted eccentrically to the said power-wheel, a weighted lever to move the said brake-shoe on 20 its pivot, and an auxiliary brake-shoe pivoted to any suitable frame-work and connected with the weighted lever by a connecting-rod, whereby the brake-shoes are moved simultaneously, all as will be hereinafter more fully set forth.

25 Figure 1 represents, in side elevation, a brake mechanism constructed in accordance with this invention and applied to a power-wheel of an elevator, and Fig. 2 a top view thereof.

30 The shaft A, supported in any usual bearings, carries a gear-wheel, B, which may actuate any usual drum over which a rope may be passed to sustain a load. The said shaft A also carries a power-wheel, A', having its 35 periphery grooved to receive the usual endless rope or chain, a, and is also provided with a flat surface against which the brake-shoe may bind, all as in the said patent referred to, so need not be herein further described.

40 The main brake-shoe b having a curved face, b', faced with leather or other yielding material, is pivoted upon a shaft, 2, placed eccentrically to the power-wheel A', said shaft 2 having bearings in the frame-work. The 45 brake-shoe b is moved on its pivot in one direction by a weighted lever, c, rigidly connected therewith, which in turn is raised by a hand cord or chain, c', passing over a pul-

ley, c², having bearings in the frame-work, said cord or chain thence passing downward 50 to be at all times accessible to the operator.

An auxiliary brake-shoe, d, constructed similarly to the brake-shoe b, is suspended from a shaft, 3, also having bearings in the frame-work, and is arranged to bind against 55 the power-wheel nearly opposite the brake-shoe b. The lower end of the auxiliary brake-shoe d is connected with the weighted lever c, as at d', by a connecting-rod, d², by which to move it.

Normally, the cord c being loose and the wheel being turned in the direction of the arrow 4 for hoisting, the parts remain as in full-line position, Fig. 1, the lower end of the brake-shoe b just touching the periphery of 65 the power-wheel, while the auxiliary brake-shoe d is removed from contact therewith, such position permitting the power-wheel A' to rotate in the direction of the arrow 4 as the operator pulls upon the rope a to raise the 70 load.

Should it incidentally be desired to stop the load, the operator releases his grasp upon the rope a, the power-wheel A' reverses its rotation by reason of the weight of the load, causing the eccentrically-pivoted brake-shoe b to immediately bind upon the periphery of the power-wheel, thus automatically stopping its backward rotation.

To lower a loaded car suspended by a rope 80 or chain from the shaft or drum A, the operator from his position on any floor will pull upon the cord c', raise the weighted lever c, and draw the eccentrically-pivoted brake-shoe b away from contact with the periphery 85 of the power-wheel A', and the wheel will commence to turn in the direction opposite the arrow 4, such movement drawing the brake toward but not against the power-wheel A'.

When the lever c has been sufficiently raised to lie in a direct line with the arrow 5, Fig. 1, both brake-shoes are removed from contact with the power-wheel, thus permitting it to rotate freely in either direction; but by raising the lever c a little farther, as into the dot-

ted-line position, Fig. 1, the brake-shoe *d* is brought in direct contact with the power-wheel, checking its rotation.

Thus it will be seen that an operator can very soon become skilled to carry his load at any desired speed with safety, and check it either by the cord or automatically.

The lever *c* has on it an adjustable weight, *c'*, which acts as a counter-balance for the rope *c'*.

I claim—

1. The power-wheel *A'*, combined with a brake-shoe, *b*, pivoted eccentrically to the axis of the shaft of the said wheel to automatically check the rotation of the power-wheel in one direction, substantially as described.
2. The power-wheel *A'* and the eccentrically-pivoted brake-shoe, combined with a lever connected with the said brake-shoe, substantially as described.

3. The power-wheel *A'*, the brake-shoe *b* and its lever, combined with an auxiliary brake-shoe, and connecting means whereby both brake-shoes are moved simultaneously, substantially as described.

4. The main brake-shoe pivoted to engage the wheel *A'*, combined with an auxiliary brake-shoe pivoted to engage the opposite side of the wheel *A'*, and connecting means whereby both brakes are moved simultaneously, substantially as described.

In testimony whereof I have signed my name to this specification in the presence of two subscribing witnesses.

JAMES A. HURLEY.
